Des. 214,755
Patented July 22, 1969

214,755

ION SENSING ELECTRODE OR THE LIKE

John McPhee, Chelmsford, Mass., assignor to Corning
Glass Works, Corning, N.Y., a corporation of New
York

Filed Mar. 29, 1968, Ser. No. 11,189

Term of patent 14 years

Int. Cl. D10—10, 99

U.S. Cl. D52—6

Fig. 1

Fig. 2

Fig. 3

Fig. 5

Fig. 4

FIGURE 1 is a side elevational view of an ion sensing electrode embodying the design.

FIGURE 2 is a view similar to FIGURE 1 illustrating the electrode with its end cap removed.

FIGURE 3 is a perspective view of the electrode with its end cap removed.

FIGURE 4 is an enlarged end view showing the tip of the electrode with its end cap removed.

FIGURE 5 is an enlarged perspective view of the tip of the electrode with its end cap removed.

The side of the electrode not shown in FIGURE 1 is a mirror image of the side shown.

The broken away showing of a cord at the far right of FIGURES 1, 2 and 3 indicates indeterminate length.

I claim:

The ornamental design for an ion sensing electrode or the like, substantially as shown and described.
